United States Patent Office.

STEPHEN B. McCACKEN, OF DETROIT, MICHIGAN.

Letters Patent No. 78,228, dated May 26, 1868; antedated May 12, 1868.

IMPROVED SPRING-BED BOTTOM.

The Schedule referred to in these Letters Patent and making part of the same.

TO ALL WHOM IT MAY CONCERN:

Be it known that I, STEPHEN B. McCACKEN, of the city of Detroit, county of Wayne, and State of Michigan, have invented a new and improved Mode of Constructing Spring-Bed Bottoms; and I do hereby declare that the following is a full and exact description thereof, reference being had to the accompanying drawings, and to the letters of reference marked thereon.

The nature of my invention consists in the use of a conical spiral spring with a wood button or disk affixed to the upper and smaller end of the same, to which a webbing or cover is affixed by a screw, or other suitable means.

To enable others skilled in the art to make and use my invention, I will proceed to describe its construction and operation, reference being had to the drawings hereto annexed.

Figure 1 represents the general appearance of the bed-bottom when complete.

Figure 2 shows the arrangement of the springs, the cover or webbing, marked B in fig. 1, being removed.

Figure 3 shows one of the springs with its attachments, and also the mode by which the cover or webbing is secured.

The wood part of the bottom is made in the ordinary way, as represented in fig. 2. The number of the springs may be whatever experience and cost may require. What I particularly claim as new is, the spring and its attachments, as shown in fig. 3, in which B shows the spring; H is the point where it is fastened to the bed-bottom; C is a wood cap or button firmly affixed in the upper end of the spring; D is a small metal cap, which is received into and fits the cavity marked F in the wooden button C; it is held firmly in its place by the screw marked E.

G G represents a section of a part of the cover or webbing, which, passing between the metal cap E and the wooden button C, is firmly held in its place, and attached to the spring B by the screw E.

The springs may be made of either brass or iron wire, or other suitable material, and of such size as may be found most suitable. The diameter also of the wooden button C may be varied to suit convenience, and the cover or webbing may be of any suitable material; it is to be securely fastened to the sides, as shown in fig. 1, after being affixed to the several springs, as shown in fig. 3.

What I claim, and desire to secure by Letters Patent, is—

The button-headed half spring fastened to the webbing or other cover by the use of a common screw and convex washer, as shown in fig. 3, substantially as and for the purpose herein described.
